DESIGN FOR A BASKET

William C. P. Zabel and Richard C. Helfenbein,
Chicago, Ill., assignors to Plasmet Corporation,
Chicago, Ill., a corporation of Illinois

Application February 15, 1947, Serial No. 136,938

Term of patent 14 years

(Cl. D58—4)

To all whom it may concern:

Be it known that we, William C. P. Zabel and Richard C. Helfenbein, both citizens of the United States and both residents of Chicago, in the county of Cook and State of Illinois, have invented a new, original, and ornamental Design for a Basket, of which the following is a specification, reference being had to the accompanying drawing, forming a part thereof, and in which:

Fig. 1 is a perspective view of a basket, showing our new design;

Fig. 2 is a side elevational view of the same;
Fig. 3 is a bottom plan view of the same.

We claim:

The ornamental design for a basket, as shown.

WILLIAM C. P. ZABEL.
RICHARD C. HELFENBEIN.
